(57) **CLAIM**

The ornamental design for a carton with curved gable panel creases, as shown and described.

DESCRIPTION

FIG. 1 is a perspective view of a carton with curved gable panel creases embodying our new design;

FIG. 2 is a front view thereof;

FIG. 3 is a rear view thereof;

FIG. 4 is a left side view thereof;

FIG. 5 is a right side view thereof; and,

FIG. 6 is a top view thereof.

The carton being shown with a closure cap in phantom lines that forms no part of the claimed design, and the bottom forming no part of the claimed design.
